UNITED STATES PATENT OFFICE.

WILLIAM H. RENN, OF ROCKY MOUNT, NORTH CAROLINA, ASSIGNOR OF ONE-THIRD
TO JAMES F. McMAHON, OF ROCKY MOUNT, NORTH CAROLINA.

EXPANSION PIPE-JOINT.

1,090,086.

Specification of Letters Patent. Patented Mar. 10, 1914.

Application filed April 10, 1913. Serial No. 760,198.

To all whom it may concern:

Be it known that I, WILLIAM H. RENN, a citizen of the United States, residing at Rocky Mount, in the county of Edgecombe 5 and State of North Carolina, have invented certain new and useful Improvements in Expansion Pipe-Joints, of which the following is a specification.

This invention relates to expansion pipe 10 joints or couplings, and is more particularly intended as an improvement upon the device set out in the United States Letters Patent No. 952,510, issued to John S. Chambers, March 22, 1910, for throttle valve.

15 The object of this invention consists in providing the tubular housing for the rock shaft shown in said patent with means permitting the housing to expand and contract longitudinally without working loose at one 20 end or the other.

The difference in expansion and contraction of the boiler with respect to the housing is also rendered harmless by the use of this invention, and steam, mud, or corroding substances are shut out from entering the stuffing box for the valve rod or rock shaft and accumulating in the mouth of the gland with consequent interference with the proper operation thereof, as has been learned from 25 experience in the practice of the invention covered by the aforesaid patent.

The accompanying drawings show so much of the said patented device as is necessary to the full explanation of this invention, and Figure 1 of the drawings shows a 35 longitudinal section of the gland, stuffing box and housing for the rock shaft, with this invention applied thereto. Fig. 2 illustrates, partly in section, the application of 40 this invention to a line of steam pipe extending in one direction or in two directions.

Throughout the drawings and description, the same letter is employed to refer to 45 the same part.

Considering Fig. 1, the rear end A of a boiler has attached thereto the stuffing box B, provided with the gland C, through both of which passes the rock shaft D. The rock 50 shaft is surrounded by the housing or pipe E, and the shaft may be turned by the crank F. Between the gland and the box B is the gland packing e. Internally, the stuffing box B is bored to receive movably the hollow 55 cylinder G which is provided with a plu-

rality of rings of packing g, making a steam-tight joint with the interior of the box B. As ordinarily made, the middle of the cylinder G is less in diameter than the ends thereof, and any steam passing the first series of packing rings g of the cylinder may be drained when condensed by way of tube b.

In the operation of this invention, still considering Fig. 1, when the boiler is cold it may contract lengthwise sufficiently to bring the cylinder G and the packing H, which represents any suitable packing for the rock shaft D where it passes outwardly through the gland C, together. As the shell of the boiler becomes heated it may expand lengthwise at a greater rate than the tubular housing E, whereupon, the box and gland would move to the left with respect to the cylinder G, and without subjecting the housing E to any undue strain.

Considering Fig. 2, the pipe coupling J contains the cylinder K, in all respects like cylinder G already described, and attached to the end of steam pipe L. The line of pipe of which pipe L forms a part may, 75 therefore, expand and contract freely.

I do not limit myself to the use of a single cylinder in a pipe coupling such as the coupling J, but may employ any number of cylinders such as the cylinder K for a corresponding number of the pipes leading to the coupling or housing.

Having now described this invention and explained the nature of its operation, what I claim is—

1. The combination with a stuffing box, of a rock shaft passing through the box, a cylinder provided with packing and arranged within the box, the said rock shaft passing movably lengthwise through said cylinder, the said box being constructed internally to receive said cylinder movably and steam tight, and a housing surrounding said rock shaft and having one end connected with the said cylinder, whereby said box and shaft and housing may move by expansion or contraction independently of each other.

2. The combination with a rear end of a boiler, of a stuffing box, a rock shaft passing through the said box, a cylinder provided with packing and arranged within the box, the said rock shaft passing movably lengthwise through said cylinder, the said box being constructed internally to receive said cylinder movably and steam tight, and a

22
housing surrounding said rock shaft within the boiler and having one end connected with the said cylinder, whereby said box and shaft and housing may move by expansion or contraction independently of each other.

3. The combination with the rear end of a boiler, of a stuffing box arranged upon the exterior of the end of the boiler, a rock shaft passing through said box, a cylinder provided with packing and arranged within the box, the said rock shaft passing movably lengthwise through said cylinder, the said box being constructed interiorly to receive

said cylinder movably and steam tight, and a housing surrounding the said rock shaft 15 within the boiler and having one end connected with the said cylinder, whereby said box and shaft and housing may move by expansion or contraction independently of each other.

20
In testimony whereof I affix my signature in presence of two witnesses.

WILLIAM H. RENN.
